STREET LIGHTING LUMINAIRE HOOD

Alfred W. Corwin, Oak Creek, Wis., assignor to McGraw-
Edison Company, a corporation of Delaware

Application July 5, 1956, Serial No. 42,153

Term of patent 14 years

(Cl. D48—31)

FIG. 1.

FIG. 2.

FIG. 3.

Figs. 1 through 3 are all perspective views of a street lighting luminaire hood, showing my new design, and respectively illustrating the hood from all sides thereof.

The broken lines in the drawing are for illustrative purposes only.

I claim:

The ornamental design for a street lighting luminaire hood, as shown and described.
